INSTRUMENT SUPPORTING DEVICE

Clyde L. Hunsicker, San Francisco, Calif., assignor of one-half to Aaron S. Green, Louis D. Green, and Martin I. Green, all of San Francisco, Calif.

Application July 20, 1936, Serial No. 91,464

8 Claims. (Cl. 248—283)

This invention relates generally to equipment for adjustably supporting various instruments, as for example ophthalmological instruments used in the testing of eyes and the fitting of glasses.

It is an object of the invention to generally improve upon apparatus of the above character whereby the instrument or device being supported can be conveniently adjusted to any desired position, and can be firmly held in such position while the instrument is in use. In the past, such apparatus has been constructed in such a manner as to be difficult to manipulate, both with respect to adjusting the instrument to a desired position, and with respect to retaining the instrument in a desired location after adjustments are made. The present invention provides a minimum number of members to be manipulated in securing a desired adjustment, and a simple mechanism is provided for retaining a given adjustment.

Further objects of the invention will appear from the following description in which the preferred embodiment of the invention has been set forth in detail, in conjunction with the accompanying drawing.

Referring to the drawing:

Fig. 1 is a side elevational view, in cross-section, illustrating an apparatus incorporating the present invention.

Fig. 2 is a cross-sectional view, taken along the line 2—2 of Fig. 1.

Fig. 3 is a plan view of a part of the arm incorporated in the apparatus of Fig. 1.

Fig. 4 is a cross-sectional view taken along the line 4—4 of Fig. 1.

Fig. 5 is a cross-sectional detail taken along the line 5—5 of Fig. 1.

The apparatus illustrated in the drawing consists of a relatively rigid mounting 10, which can be secured to some fixed structure, as for example the wall 11 of a room. Associated with the mounting 10 there is a carriage 12, to which in turn is secured a laterally extending arm 13. The free end of arm 13 carries a bar or like member 14, to which an ophthalmological instrument can be secured, or any other device or instrument which the operator wishes to support in an adjustable position. As will be presently explained the carriage 12 can be adjusted in a vertical position with respect to the mounting 10. Likewise the carriage together with the arm 13 can be adjusted in a horizontal plane about a vertical axis, and the angular setting of bar 14 can be varied with respect to the longitudinal axis of the arm 13.

A guide or tracking means for the carriage 12, is preferably constructed as follows: The mounting 10 includes upper and lower retaining members 16 and 17, which are each generally annular in form, with substantially cylindrical bores 18. Rotatably retained within each of the members 16 and 17, are the discs 19 and 20. Vertically extending tracking elements 22, 23 and 24 are provided, which can be in the form of relatively rigid steel rods. The upper and lower ends of these rods are fixed to the discs 19 and 20. A suitable spacing for the rods 22, 23 and 24 is shown in Fig. 4, in which their axes are disposed coincident with the corners of an equi-lateral triangle, and with the axis of the two rods 23 and 24 being disposed at equal distances from the surface of the wall 11, when the axis of the arm 13 is at right angles to the plane of the wall.

The carriage 12 can be in the form of a suitable casting, to which two sets of guide rollers 26 and 27, are journaled. The general plane of rollers 26 is at an acute angle to the plane of rollers 27, so that each roller 26 is adapted to engage the rods 22 and 24, while each roller 27 is adapted to engage rods 22 and 23. With such an arrangement it is apparent that carriage 12 will be adequately guided for vertical movements, and that sufficient strength will be afforded so that arm 13 may carry a substantial weight. Likewise it will be understood that the carriage 12, together with arm 13, can be swung in a horizontal plane about a vertical axis coincident with the centers of discs 19 and 20, and in making such adjustments the guide rods 22, 23 and 24 turn in unison with the carriage 12 and 13.

The main length of arm 13 can be formed of a rigid metal tube 13a. One end of this tube is shown having a rigid telescopic connection with the main casting of carriage 12, while the other end is shown having a rigid telescopic connection with a hollow extension casting 31.

In order to facilitate making vertical adjustments of the arm 13, means are provided as follows: Journaled with the extension 31 there is shaft 32, the outer end of which carries a hand wheel 33 or like operating member. An inner portion of shaft 32 carries a pinion 34, adapted to engage a tooth rack 36. Rack 36 is secured to one end of a rod 37, and this rod extends longitudinally through the tube 13a, to a point near the carriage 12.

Associated with the carriage 12 there is a flexible cable or chain 38. One end of this chain is anchored to the carriage, as indicated at 39, and the other end is suitably anchored to the

- disc 19. For example the one end of the chain has been shown secured to a threaded rod 41, which extends upwardly through the disc 19, and is engaged by a nut 42 at its upper end. 5 This chain is tracked over sprocket 43, which is journaled to the carriage, and also to a sprocket 44, which is journaled to the adjacent end of rod 37. Thus when the hand wheel 33 is turned to move sprocket 44 towards the right as viewed 10 in Fig. 1, the carriage 12 is moved upwardly with respect to the mounting 10, and vice versa, when the hand wheel 33 is turned in the opposite direction, to move sprocket 44 to the left, the carriage moves downwardly. 15 In order to enable vertical adjustments of the arm 13 to be made with the least possible effort, it is desirable to provide counterbalancing means to compensate for the weight of the moving parts. The counterbalancing means illustrated consists 20 of a compression spring 46, one end of which is seated upon the carriage 12, and the other end which is seated upon a follower 47. Within the compression spring 46 there is a tension spring 48, having its one end anchored to the follower 25 47, and its other end anchored to the rod 37 as indicated at 49. Follower 47 is free to slide longitudinally over the rod 37. It will be evident that compression spring 46 tends to urge follower 47 to the right as viewed in Fig. 1, and 30 such force is applied as tension to spring 48, which in turn applies force to rod 37, in a direction to tension the chain 38. This type of counterbalancing makes it possible to entirely compensate for the weight of the vertically adjustable parts, 35 without however interfering with lowering of the arm when the hand wheel 33 is turned in the proper direction.
- The pivotal connection between member 14 and the arm 13, can be constructed as follows: Member 40 14 is secured to a casting 51, which is forked as illustrated to provide upper and lower portions 52 and 53 of a pivotal connection. Complementary portions 54 and 55, are formed on the extension casting 31. Extending through these 45 portions there is a tubular shaft 56. This shaft is free to rotate in portions 52 and 53, and is fixed with respect to portions 54 and 55, so that member 14 can be turned at various angles in a horizontal plane, with respect to the axis of arm 13. 50 In the foregoing I have described the means incorporated in my apparatus enabling adjustment in a vertical direction, swinging adjustment of the entire arm 13 about a vertical axis, and individual angular adjustment of the member 14, with respect to the longitudinal axis of the arm 13. I shall now describe means whereby 55 braking forces can be applied, to retain any instrument attached to member 14 relatively steady and in a fixed position. A shaft 51 is journaled to the extension casting 31, and one end of this shaft is secured to an operating lever 58. An arm 59 is secured to an inner portion of the shaft 57, and carries a cam roller 61. Disposed 60 within the hollow shaft 56, there is a slidable plunger 62. This plunger is urged downwardly by compression spring 63, the upper end of which is shown seated upon a retaining cap 64. Plunger 62 has a pivotal connection 66 with one arm of a lever 67. This lever has a fulcrum connection 68 with the extension casting 31, and its other arm is provided with a cam surface 69, adapted 70 to be engaged by the cam roller 61. When the lever 67 is in the position illustrated in Fig. 1, lever 67 retains plunger 62 against the urge of 75

spring 63. When lever 67 is moved to the right as viewed in Fig. 1, it is released from dead center position, and the urge of the spring 63 moves plunger 62 downwardly, with rotation of lever 67 in a clockwise direction.

In the lower portion of tubular shaft 56, there is a second slidable plunger 71. Extending laterally from this plunger are the pins 72, which are accommodated in slots 73, formed in the lower end of the tubular shaft 56 (Fig. 5). The outer ends of pins 72 are in turn secured to an annular clutch ring 74. An annular recess 76 in portion 53 serves to accommodate the clutch ring 74, and complementary conical surfaces 77 are provided, whereby when ring 74 is forced 15 downwardly, it is caused to frictionally grip portion 53.

Plungers 62 and 71 are interconnected by the links 78 and 79. The common pivotal connection 81 between these links also forms a pivotal 20 connection with one end of an actuating rod 82, which in turn serves to actuate braking means associated with the carriage 12. This mechanism makes use of parts which also incidentally serve to house a major part of the carriage 12, and 25 the tracking rods 22, 23 and 24. Thus the tracking rods are enclosed by the segmental curved members 83, which extend between the discs 19 and 20. A slot or gap 84 on the front side of the housing so formed, has sufficient width to 30 accommodate vertical movements of the carriage. The upper and lower edge portions of the members 83 extend into the bores 18, formed in the retaining members 16 and 17. Thus when the members 83 are expanded in a general radial direction, their upper and lower edges are caused to frictionally grip the adjacent inner peripheral surfaces 18 of the members 16 and 17. The expansion of members 83 is accomplished by means of a shoe 86 (Fig. 4) which is 40 suitably mounted upon the carriage 12. For example the carriage can be provided with spaced lugs 87, within which projecting portions 88 of the shoe are accommodated. The free ends of the shoe 86 are pivotally connected to a pair 45 of links 89, which in turn have a common pivotal connection 90 with the adjacent end of rod 82. It will be noted that rod 82 extends on the lower side of arm 13, from the links 78 and 79 back to the carriage, for connection with the links 89. 50 When rod 82 is moved to the left as viewed in Fig. 4, force transmitted through links 89 causes expansion of shoe 86, to frictionally engage the segmental members 83, and in turn cause the upper and lower edge portions of these members 55 to frictionally grip the retaining portions 18 of the mountings 16 and 17.

It has been previously pointed out that when the operating lever 58 is moved to the right as viewed in Fig. 1, plunger 62 is free to move downwardly under the urge of spring 63. Since downward movement of the second plunger 71 is limited, and likewise since movement of rod 82 towards the carriage is limited, spring 63 will apply force to the actuating rod 82, and simultaneously 60 downward force upon the plunger 71, through the links 78 and 79. Such force applied to the rod 82, causes the shoe 86 to frictionally grip the segmental members 83, and likewise causes these members to effect a gripping action with respect to the fixed mounting. Downward force applied to plunger 71 also causes the clutch ring 74 to 65 frictionally grip the adjacent conical surface of portion 53, thus applying a frictional grip serving to prevent a shift in angular relationship between 70 75

member 14 and the longitudinal axis of arm 13. Thus by manipulation of a single lever 58, after desired adjustments have been made, the carriage and also the arm 13 can be firmly held in a fixed position, both with respect to its height, and also with respect to swinging movement about a vertical axis. Likewise angular positioning of member 14 with respect to the longitudinal axis of the arm, is firmly held, so that the instrument attached to member 14 is held steady in a desired position.

If the operator desires to make adjustments it is only necessary to return lever 58 to its position as illustrated in Fig. 1. The operator may now adjust the arms 13 to a desired vertical position, by turning the hand wheel 33. He may also swing the arm to different angles with respect to the wall, and may turn member 14 at various angles with respect to the longitudinal axis of the arm. It will be noted that such adjustments are facilitated because the hand wheel is located at a point which is not far removed from the instrument attached to member 14. Likewise the lever 58 is in a convenient position to be manipulated, after adjustments have been made.

I claim:

1. In an adjustable support for instruments, a relatively fixed mounting, vertically extending tracking means carried by said mounting, said tracking means being rotatable about a vertical axis with respect to said mounting, a vertically movable carriage engaging said tracking means, a laterally extending arm having one end of the same secured to said carriage, an operating member mounted upon said arm at a point remote from said carriage, a member extending longitudinally within said arm and adapted to be reciprocated by movement of said operating member, spring means carried within said arm and serving to counterbalance the weight of the carriage and said arm, and means operatively connected to said reciprocable member and serving to effect vertical adjustment of said carriage on said arm, by movement of said operating member.

2. In an adjustable support for instrument, a relatively fixed mounting, vertically extending tracking means carried by said mounting, said tracking means being rotatable about a vertical axis with respect to said mounting, a vertically movable carriage engaging said tracking means, a laterally extending arm having one end of the same secured to said carriage, an operating member mounted upon said arm at a point remote from said carriage, a member extending longitudinally within said arm and adapted to be reciprocated by movement of said operating member, spring means carried within said arm and serving to counterbalance the weight of the carriage and said arm, and means operatively connected to said reciprocable member and serving to effect vertical adjustment of said carriage on said arm, by movement of said operating member, said last means including a flexible cable having one end of the same fixed with respect to the mounting and the other end of the same fixed to the carriage.

3. In an adjustable support for instruments, a relatively fixed mounting including upper and lower retaining members, vertically extending tracking means having their upper and lower ends journaled with respect to said retaining members, a carriage engaging said tracking means for vertical movement, an arm having one end of the same secured to said carriage and extending laterally from the mounting, means car-

ried by the free end of said arm for attachment of an instrument, means for effecting vertical adjustment of said carriage with respect to said tracking means, an expansible housing substantially embracing said tracking means, the upper and lower edge portions of said housing being adapted to frictionally engage portions of said mounting, when said housing is expanded, and means supported by the carriage for releasably expanding said housing.

4. In an adjustable support for instruments, a relatively fixed mounting having upper and lower retaining members, vertically extending tracking means, said tracking means having its upper and lower ends journaled with respect to said retaining members for rotation about a vertical axis, a carriage engaging said tracking means and movable thereon in a vertical direction with respect to the mounting, an arm having one end of the same secured to said carriage and extending laterally from the mounting, a housing surrounding said tracking means, said housing being expansible and having upper and lower portions thereof adapted to grip portions of said mounting, when said housing is expanded, a movable operating member carried by said arm, expansible shoe means carried by said carriage and engageable with the inner periphery of said housing, and means connecting said operating member with said shoe means to effect expansion of said shoe means to grip the housing and to cause consequent expansion of said housing to grip said portions of the mounting.

5. In an adjustable support for instruments, a relatively fixed mounting, vertically extending tracking means, said tracking means being journaled with respect to said mounting, whereby said tracking means may rotate about a vertical axis, a carriage engaging said tracking means for vertical movement with respect to said mounting, a laterally extending arm having one end of the same secured to said carriage, means serving to counterbalance the weight of the carriage and said arm, and a tubular casing surrounding said tracking means, said casing being rotatable about a vertical axis together with said tracking means and having a vertical extending slot in one side of the same, to accommodate vertical movements of said carriage.

6. In an adjustable support for instruments, a relatively fixed mounting, vertically extending tracking means, means for journailling said tracking means with respect to said mounting, whereby the tracking means is rotatable about a vertical axis, a carriage engaging said tracking means and capable of vertical movement with respect to the same, a laterally extending arm having one end of the same secured to said carriage, and means serving to counterbalance the weight of the carriage and said arm, said means including a flexible retention element having one end of the same attached to the upper end of the tracking means and having the other end of the same attached to the carriage, a wheel engaging a laterally extending loop formed in said element, and a counterbalancing spring carried by the arm and serving to urge said wheel in a direction to tension said element.

7. In an adjustable support for instruments, a relatively fixed mounting, vertically extending tracking means, means for journailling said tracking means to said mounting, whereby the tracking means can be rotated about a vertical axis, a carriage engaging said tracking means and capable of vertical movement with respect to the

tracking means and said mounting, a laterally extending arm having one end of the same secured to said carriage, a tubular housing surrounding said tracking means, said housing having a vertical slot formed in the same to accommodate vertical movements of said carriage, and counterbalancing means for the carriage and said arm, said counterbalancing means including a flexible retention element having one end of the same connected to one end of the tracking means and the other end of the same connected to the carriage, and a spring carried by the arm and serving to tension said element.

8. In an adjustable support for instruments, a relatively fixed mounting, three vertically ex-

tending track elements carried by the mounting, said track elements being fixed in spaced relationship with respect to each other and being rotatable about a vertical axis with respect to the mounting, a carriage, a laterally extending arm having one end of the same secured to the carriage, two sets of rollers secured to the carriage and engaging said track elements, the two sets of said rollers being disposed respectively in two planes which are at an acute angle with respect to each other, whereby the two sets of rollers engage one track element in common, and means carried by the other end of said arm for the mounting of an instrument.

CLYDE L. HUNSICKER. 15
